(57) **CLAIM**

The ornamental design for a support element for hanging light fixture as shown and described.

DESCRIPTION

FIG. 1 is an isometric view of a support element for hanging light fixture showing our new design;

FIG. 2 is a left side view thereof;

FIG. 3 is a right side view thereof;

FIG. 4 is a top plan view thereof;

FIG. 5 is a bottom plan view thereof;

FIG. 6 is a front view thereof;

FIG. 7 is a rear view thereof;

FIG. 8 is an isometric view of a support element for hanging light fixture showing an alternate embodiment of our new design;

FIG. 9 is a left side view thereof;

FIG. 10 is a right side view thereof;

FIG. 11 is a front view thereof;

FIG. 12 is a rear view thereof;

FIG. 13 is a top plan view thereof;

FIG. 14 is a bottom plan view thereof;

FIG. 15 is an isometric view of a support element for hanging light fixture showing another alternate embodiment of our new design;

FIG. 16 is a front view thereof;

FIG. 17 is a rear view thereof;

FIG. 18 is a left side view thereof;

FIG. 19 is a right side view thereof;

FIG. 20 is a top plan view thereof; and,

(Continued)

FIG. 21 is a bottom plan view thereof.

1 Claim, 12 Drawing Sheets
